Primary Examiner — Eric Goodman*Assistant Examiner* — Jennifer L Rempfer(74) *Attorney, Agent, or Firm* — Buche & Associates, PC; John K. Buche(57) **CLAIM**

I claim the ornamental design of an orthopedic pillow, as shown and described.

DESCRIPTION

FIG. 1 is a top perspective view of the pillow highlighting the cut out which is the claimed part of the design.

FIG. 2 is a top view of the pillow highlighting the cut out which is the claimed part of the design.

FIG. 3 is a bottom view of the pillow highlighting the cut out which is the claimed part of the design.

FIG. 4 is a left-side view of the pillow.

FIG. 5 is a right-side view of the pillow.

FIG. 6 is a front view of the pillow; and,

FIG. 7 is a back view of the pillow.

The broken lines of the Figures illustrate structure and portions of the pillow that form no part of the claimed design.
